UNITED STATES PATENT OFFICE.

GEORGE GIBBS, OF PATERSON, NEW JERSEY, ASSIGNOR OF ONE HALF TO
ISAAC SMITH, OF SAME PLACE.

ALARM-LOCK.

SPECIFICATION forming part of Letters Patent No. 379,642, dated March 20, 1888.

Application filed December 29, 1887. Serial No. 259,350. (No model.)

To all whom it may concern:

Be it known that I, GEORGE GIBBS, a subject of the Queen of Great Britain, residing at Paterson, Passaic county, State of New Jersey, 5 have invented a new and useful Improvement in Alarm-Locks, of which the following is a specification, reference being had to the accompanying drawings, forming a part thereof.

My invention relates to locks for trunks, 10 chests, tills, &c., and has for its object the construction of an alarm-lock wherein every action of the key upon the lock mechanism shall sound an alarm.

My invention consists in certain features of 15 construction and combination of parts, as will be hereinafter fully described, and pointed out in the claim.

Figure 1 of the drawings is a part sectional elevation of the lock, in which figure a portion 20 of the covering-plate is removed; and Fig. 2 is an elevation of the same, the covering-plate being entirely removed in such figure.

A represents an alarm-lock for trunks, chests, 25 tills, &c., having the usual guide-pin, a, fastening-plate b, rim c, and covering-plate c'. On the guide-pin a, which is adapted to guide the key a' in position to act upon the lock mechanism, is arranged a revolving ward, C. This revolving ward C is composed of a wheel portion 30 having a series of engaging lugs or teeth, d, and a stem portion adapted to receive and accommodate the key a' of the lock A. The wheel portion of the ward C is arranged to fit the guide-pin a and revolves against the plate 35 b, while the stem portion of the same is cut to fit the wards in the key on the under side of the stem, and is therefore adapted to be turned by the key a' in the operation of locking and unlocking.

In position to be acted upon by the lugs or 40 teeth d of the revolving ward is a cam, e, which cam is arranged partly behind a plate, i, on a pin, J, which pin passes through plate i and holds the same in position while the pin is 45 fixed in the fastening-plate b. On a stud, K, more remote from the center of motion, is arranged a hammer, g, which hammer passes horizontally over the cam e and in position to be acted upon by the same, and extends to a 50 gong, h, which gong is fixed on a stud, h', held by a screw, h'', said stud h' being fastened in

the plate b of the lock A. The hammer g is provided with a spring, g', which spring bears on the upper side thereof and acts to throw said hammer into forcible contact with the 55 gong, the spring being arranged on a stud, g'', fixed in the fastening-plate b. On a stud, n'', fixed in the plate b, is arranged a tumbler, n, that rests on the plate i, which tumbler has a spring portion, i', and a projecting catch portion, n', and is arranged to be acted upon by the key a', and is located partly behind a bolt, S, which bolt slides against the rim c, when moved by the key a', and is engaged by the projecting catch portion n' of the tumbler. 60 The bolt S is provided with depending lugs t t', the former to be acted upon by the key a' in unlocking the device and the latter to be acted upon by the key when locking the same, while the bolt has arranged on its upper edge notches 65 r r', for engagement with the tumbler.

The key a' is inserted in the key-hole a'' and is turned forward with the revolving ward, which action puts the lugs d of the ward C into engagement with the cam e, four of which lugs 75 d will have engaged the cam and caused the latter to raise the hammer g to be thrown by the spring g', in each one of the four engagements required in unlocking, into contact with the gong h, and thus sound four alarms on the 80 gong in the operation. When three of the engaging-lugs d of the revolving ward C have acted upon the cam and three alarms have been given by the action of the hammer on the gong actuated by the spring g' on the escape of the 85 cam from the action of the ward, the key a' will then be in position to throw the bolt S to the right-hand side, having previously acted upon the tumbler n and lifted the catch n' out of the notch r' preparatory to throwing the bolt 90 S by engaging the lug t thereof, as seen in Fig. 2, which, when done, the fourth alarm will be given by the action of the hammer on the gong caused by the spring under the fourth action of the ward C on the cam e. The bolt S having 95 been thrown in the manner stated, the catch n' enters the notch r', and the lock-plate m is freed from the bolt S and the lock is unlocked. The bolt having been thrown and the lock unlocked, the key a' will be between lugs t t' of 100 the bolt S and in position to engage lug t' of said bolt and throw the same to the left-hand

side and lock the lock by sounding one alarm on the gong by the action of the ward C on the cam e, in the manner before stated; but three additional alarms will be given before 5 the key a' will be in position to be withdrawn from the lock through key-hole a². Thus it will be seen that when the key a' is inserted in the lock through the key-hole a² four alarms will be sounded in the operation of locking 10 or unlocking, and that no action can be had by the key on the lock mechanism without the sounding of an alarm by the gong.

A greater or a less number of engaging-lugs d may be arranged on the wheel portion of the 15 ward C, by which a less or greater number of alarms are given in the operation of locking and unlocking without changing materially the nature of my invention; hence I do not confine myself to this particular construction 20 of the wheel portion of the ward C.

Having described my invention, what I claim as new, and desire to secure by Letters Patent, in a lock for trunks, chests, tills, &c., is—

The combination, with the revolving ward having lugs d thereon and a key for turning 25 said ward, of the tumbler n, the bolt S, having notches r r' and lugs t t', the cam e, the hammer g, engaged by the cam, the gong h, spring g', plates b and i, rim c, lock-plate m, and pin a, arranged and operating so that no action 30 can be had by the key on the locking mechanism without sounding the alarm, substantially as set forth.

GEORGE GIBBS.
